(54) **BUTTONS,HOLDFAST WHILE POLISHING**

(76) Inventor: **Ira Ives**

The schedule referred to in these Letters Patent, and making part of the same, containing a description in the words of the said Sir ~~John~~ himself of his Button Holafast.

The hook and spring are attached to the stock, which screws into the mandrel, having a suitable surface in the middle to receive the eye of a button.

A mortice is made in the stock, about one inch in length, one eighth of inch wide, leaving the lip of the opening entire. Into this mortice a piece of iron called the hook is fitted, fastened by a pin or rivet, or which it plays about three fourths of an inch from the end of the stock where the eye of the button is mounted, and having a hook on the end which goes into the mortice fitted to enter the eye of the button, and connects therewith a shaft about three inches in length rising from the part in an angle of about twenty degrees. On and in the shaft at the end opposite to where the eye of the button is mounted, is fitted a spring, resting back on the stock, tending to keep the hook arm in its place. The end of the hook which enters the eye, must be tapered nearly to a point, swelling toward the shoulders, on the side furthest from the button in the form of a wedge.

The shaft of the hook being pushed down by the hand, the hook will be drawn out of the way, and the eye of the button, being inserted into the open end of the hook shaft, let go the spring forces the point of the hook into the eye, and being of a wedging form has a constant tendency by the force of the spring to draw the button closer about it from the face of the stock during the process of turning. When finished the button is released by simply pushing down the shaft, the machine is instantly ready to receive another.

The objects aimed at in this invention are in position a comfortable seat-secure of the button. Both are attained. Nothing of the kind yet discovered, is so comfortable, and nothing heretofore has been found so effectually to secure a button from shaking as on the wedging head a spring, which holds all that is joined together, in the operation of finishing a button.
